UNITED STATES PATENT OFFICE.

OSCAR JOHNSON, OF NEW YORK, N. Y., ASSIGNOR TO AUTO PNEUMATIC ACTION COMPANY, A CORPORATION OF NEW YORK.

PEDAL AND PANEL OPERATING MECHANISM.

1,252,446.

Specification of Letters Patent.

Patented Jan. 8, 1918.

Application filed July 24, 1916. Serial No. 110,861.

To all whom it may concern:

Be it known that I, OSCAR JOHNSON, a subject of the King of Sweden, residing at New York, in the county of New York and 5 State of New York, have invented a new and useful Pedal and Panel Operating Mechanism, of which the following is a specification.

This invention relates to pedal and panel 10 operating mechanism particularly designed for use in player pianos. In such instruments pedals are employed to operate the bellows when the player mechanism is to be used, and these pedals are arranged to be 15 folded back inside of the piano casing when the player mechanism is not in use. The opening in the casing is closed by a door or panel after the pedals have been folded back. It is desirable and customary to provide a 20 single mechanism for performing both of these operations in fixed sequence, and it is the general object of my invention to improve and simplify the mechanism used for thus moving these elements in definite relation to each other.

To the accomplishment of this object my 25 invention consists in certain arrangements and combinations of parts which will be hereinafter described and more particularly 30 pointed out in the appended claim.

A preferred form of my invention is shown in the drawings in which—

Figure 1 is a front elevation of my improved mechanism, showing the panel raised 35 and the pedals in operative position;

Fig. 2 is a partial front elevation showing the parts in the position which they assume when the case is closed;

Fig. 3 is an enlarged detail view of a portion of the bell crank for raising the panel;

Fig. 4 is a side elevation of the parts employed in moving the pedal frame;

Fig. 5 is a view similar to Fig. 4, but showing the parts in a different position;

Fig. 6 is an enlarged detail view of the operating shaft and the connections thereto, and

Fig. 7 is a view similar to Fig. 6 but with the parts in a different position.

Referring to the drawings, a portion of a piano casing 10 is shown, having an opening 11 normally closed by a vertically sliding panel 12. The panel 12 is connected by a link 13 to one arm of a bell crank 14 mounted on a fixed pivot 15. The second arm of

the bell crank is connected by an adjustable link 16 to one arm 17 of a bell crank which is rigidly secured to an operating shaft 18 mounted in fixed bearings 19 and having a handle 20 at its forward end. The link 16 has a lost motion connection to the arm 17. As herein shown this connection comprises a slot 21 formed in the link and a stud or pin 22 secured to the arm 17.

A tension spring 23 is fixed at its lower end to the frame of the casing 10 and at its upper end is connected to a projection or arm 24 fixed to the bell crank 14. The disposition of the spring is such that its line of action gradually approaches the pivot 15 of the bell crank 14 as the panel 12 descends, and it moves away from the pivot as the panel rises. This change in leverage more than offsets the change in the length of the spring, and consequently the spring counter-balances the panel when in its raised position but has comparatively little resistive force when the panel is in its lowered position. When the panel is raised the spring retains the panel in raised position without assistance from the operating mechanism.

The pedals 30 (Fig. 4) are mounted upon a frame 31 connected by arms 32 to a shaft 33 pivotally mounted in bearings 34 secured to the casing 10. An arm 35 is fixed to the shaft 33 and is adjustably connected by a link 36 to a bell crank 37 (Fig. 1) pivoted at 38 to a block 39 secured to the casing 10. The link 36 is formed in two parts which are screw-connected and provided with check nuts by which means the length of the link may be varied.

The second arm of the bell crank 37 is connected to an adjustable link 40 pivoted at 40^a to the second arm 41 of the bell crank 95 fixed to the shaft 18. Partial rotation of the shaft 18 by means of the handle 20 causes the arm 41 through the link 40 to move the bell crank 37 and to thus swing the pedals to the desired position.

A spring 42 (Figs. 4 and 5) is connected at 43 to the casing and at 44 to one of the arms 32 which position the pedal frame 31. This spring partially counterbalances the weight of the pedals when in lowered position. A leaf spring 45 is secured to the bottom of the casing 10 and is engaged by one of the arms 32 when the pedals are folded back, thus reducing the shock as the pedals come to rest. The weight of the pedals and 105 110

pedal frame is so disposed with reference to the axis of the shaft 33 that the pedals complete their movement in either direction by gravity without necessary assistance from the operating handle, and they are in a stable position of rest at both ends of their path of travel.

The sequence of operation is as follows:— Assuming that the instrument is open, as shown in Fig. 1, and the handle 20 is moved to the right, as indicated by the arrow, the arm 41 acting through the link 40, the bell crank 37 and link 36, will swing the pedals back inside of the casing. During this operation the panel will be held in its raised position by its spring 23. The stud 22 in the arm 17 will move idly along the slot 21 in the link 16 and when the pedals reach their folded position the parts will be as indicated in Fig. 6. Continued movement of the handle moves the pivot 40^a in the arm 41 across the dead center with reference to the link 40. Such movement results in a very slight longitudinal movement of the link 40 and owing to the looseness of the several connections, this movement has no effect upon the pedals or pedal frame. At this time, however, the arm 17 is moving from the position shown in Fig. 6 to the position shown in Fig. 7, and the pin 22 pressing against the left-hand end of the slot 21 positively moves the panel 12 to closed position. When the case is to be opened, the operations are performed in the reverse order. The pin 22 first moves into engagement with the outer end of the slot 21 and then raises the panel 12 while the pivot 40^a is moving idly from the position shown in Fig. 7 to the position of Fig. 6. Thereafter the pin 22 moves idly back along its slot 21 while the pedal frame is swung outwardly to operative position.

It will be seen therefore that I have provided an extremely simple operating mechanism by which the parts may be moved in

their proper sequence to their operative and inoperative positions. The movements are all obtained from a single operating shaft through simple bell crank and link connections, but nevertheless the proper relation of the movements is secured.

Having thus described my invention it will be evident that other changes and modifications can be made therein by those skilled in the art without departing from the spirit or scope thereof as set forth in the claim, and I do not wish to be otherwise limited to the details herein disclosed, but what I claim is:—

In a player piano, in combination, a casting having an opening therein, a panel for said opening, pedals mounted on a pedal frame movable through said opening into and out of operative position, and mechanism for moving said panel and pedal frame in timed relation, said mechanism comprising an actuating shaft having a handle and two actuating arms fixed thereto, a bell crank mounted on a fixed pivot and directly and positively link-connected to said panel, a slotted link forming a direct lost-motion actuating connection from one of said arms to said bell crank, a second bell crank also mounted on a fixed pivot, a link directly and positively connecting said second bell crank to an arm rigidly connected to said pedal frame and movable therewith, and a link directly connecting the second arm on the actuating shaft to said second bell crank, said lost-motion connection in the panel moving mechanism permitting said panel to be opened in advance of the forward movement of said pedal frame and to be closed after reverse movement thereof.

In testimony whereof I have hereunto affixed my signature.

OSCAR JOHNSON.
